UNITED STATES PATENT OFFICE

163,376

DRINK MIXER

W. Arthur Ernst, Racine, Wis.

Application July 22, 1950, Serial No. 11,349

Term of patent 14 years

(Cl. D44—1)

To all whom it may concern:

Be it known that I, W. Arthur Ernst, a citizen of the United States, residing at Racine, in the county of Racine, and State of Wisconsin, have invented a new, original, and ornamental Design for a Drink Mixer, of which the following is a specification, reference being had to the accompanying drawing, forming part thereof.

Fig. 1 is a view in perspective of a drink mixer showing my new design.

Fig. 2 is a view on a reduced scale in rear elevation with portions of the side wall broken away to expose the column and motor casing in vertical section.

Fig. 3 is a view taken in horizontal section on line 3—3 of Fig. 2.

Fig. 4 is a plan view of the drink mixer.

I claim:

The ornamental design for a drink mixer, as shown.

W. ARTHUR ERNST.
